UNITED STATES PATENT OFFICE.

HEINRICH WALDES, OF WRSCHOWITZ, NEAR PRAGUE, AUSTRIA-HUNGARY.

SPRING-PRESSED BUTTON ATTACHMENT.

1,151,310.

Specification of Letters Patent. Patented Aug. 24, 1915.

Application filed April 19, 1913. Serial No. 762,189.

To all whom it may concern:

Be it known that I, HEINRICH WALDES, a citizen of the Austro-Hungarian Empire, and residing at Wirschowitz, near Prague, 5 Bohemia, Austro-Hungarian Empire, have invented certain new and useful Improved Spring-Pressed Button Attachments, of which the following is a specification.

The present invention relates to that class 10 of spring pressed button attachments in which the hood part is provided with a lateral indentation, and the object is to prevent the hood from being tipped off the button. This object is attained by providing the 15 plate of the button head with a rib, adapted to engage in the lateral or radial recess formed in the hood part. By means of this arrangement the closure is secured against lateral strain and the hood is prevented from 20 rotation in respect to the button and from being tipped off the same.

In the accompanying drawings Figure 1 is a plan of the button hood, Fig. 2 a central vertical section and Fig. 3 a plan of the button plate.

The parts of this button attachment hitherto known are the upper part *a* with the hood *b* and spring *c* extending through 30 slots in the hood, furthermore the hood *b* having the hollow radially extending lateral extension *g*, forming the lateral neck of the hood.

According to the invention, the plate *d* of the button head *e* is provided with a radial 35 rib *f* adapted to engage the hollow extension *g*. This arrangement of the parts enables

the button to be attached to the garment as was hitherto the case, the button may also be manufactured in the same way as it has always been done, the only difference being 40 that during the pressing operation the hollow rib *f* is formed.

The hood *b* is provided at its junction with the radial extension *g* with an inward projection *h*, which projects slightly under 45 and engages with the bulging portion of the head *e* at the junction therewith of the rib *f*. The radial extension *g* with its projection *h* acting in conjunction with the bulging head *e* at the end of the rib *f* serves 50 to prevent rotation and tilting.

I claim as my invention:—

A separable fastener comprising a stud member including an attaching plate, a headed stud thereon and a radial rib extending outward from said stud below the bulging portion of said head toward the edge of said plate, and a socket member including an attaching plate having a hood adapted to be engaged by said stud, a hollow radial extension adapted to be engaged by said rib and an inward projection extending under the bulge of said head at the inner end of said extension, whereby rotation and tilting of said socket member are prevented. 60 65

In testimony whereof I affix my signature in the presence of two witnesses.

HEINRICH WALDES.
